US00D785695S

(12) **United States Design Patent** (10) **Patent No.:** **US D785,695 S**
Woodman et al. (45) **Date of Patent:** **** May 2, 2017**

(54) **CAMERA**

(71) Applicant: **GoPro, Inc.**, San Mateo, CA (US)

(72) Inventors: **Nicholas D. Woodman**, Woodside, CA (US); **Fred Bould**, Menlo Park, CA (US); **Kristen Beck**, San Mateo, CA (US); **David Christophe Northway**, San Carlos, CA (US); **David Andres Guasca**, San Mateo, CA (US); **Karen Ann Baumgartner**, San Mateo, CA (US); **Scott Patrick Campbell**, Belmont, CA (US); **Rudy Lucas Samuels**, Mill Valley, CA (US); **Fabrice Barbier**, San Carlos, CA (US); **Evan L. Coons**, San Mateo, CA (US)

(73) Assignee: **GoPro, Inc.**, San Mateo, CA (US)

(**) Term: **15 Years**

(21) Appl. No.: **29/552,016**

(22) Filed: **Jan. 19, 2016**

Related U.S. Application Data

(63) Continuation of application No. 29/512,084, filed on Dec. 16, 2014, now Pat. No. Des. 751,131, which is a continuation of application No. 29/491,396, filed on May 20, 2014, now Pat. No. Des. 737,879, which is a continuation of application No. 29/432,151, filed on Sep. 13, 2012, now Pat. No. Des. 721,395.

(57) **CLAIM**

The ornamental design for a camera, as shown and described.

DESCRIPTION

FIG. 1 is a front, top and right side perspective view of a camera showing our new design;

FIG. 2 is a front, bottom and left side perspective view thereof;

FIG. 3 is a rear, top and left side perspective view thereof;

FIG. 4 is a rear, bottom and right side perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken lines depict portions of the camera in which the design is embodied and form no part of the claimed design.

1 Claim, 10 Drawing Sheets
